UNITED STATES PATENT OFFICE.

HARRY STEVENSON, OF KEARNY, NEW JERSEY, ASSIGNOR TO BRANDES LABORATORIES, INC., OF NEWARK, NEW JERSEY, A CORPORATION OF NEW JERSEY.

ELECTROMAGNETIC SOUND REPRODUCER.

Application filed July 16, 1926. Serial No. 122,853.

My invention relates broadly to electromagnetic sound reproducers and more particularly to a sound reproducer employing a conical shaped sound reproducing diaphragm for the reproduction of musical notes over the entire range of frequencies encountered in radio broadcast reception.

My invention relates to that class of cone speakers which depend for their operating characteristics upon a sound amplifying cabinet in which the cone diaphragm is housed, as shown more particularly in copending application for Letters Patent, Ser. No. 60,128, filed October 2, 1925 by Cyril A. Brigham and David H. Moss.

One of the objects of my invention is to provide a simplified construction of cone speaker capable of manufacture and production inexpensively on a large scale.

Still another object of my invention is to provide a cone speaker having its parts arranged in such manner that shipment and assembly of the loud speaker may be facilitated and adjustment secured without the employment of expert or skilled labor.

Another object of my invention is to provide a cone speaker having a sound reproducing diaphragm which is supported directly from its apex through the mounting which carries the electromagnetic driving mechanism whereby the complete electromagnetic operating mechanism may be mounted upon the base which carries the sound amplifying cabinet.

A still further object of my invention is to provide an electromagnetic operating mechanism for a cone speaker wherein adjustment may be made between the electromagnets and the driving armature for the reproduction of sound at maximum tone quantity for different signal characteristics.

Still another object of my invention is to provide a cone speaker in which a single casting is provided for forming the sole means of support for the conical sound reproducing diaphragm and an electromagnetic driver which is adjustably positioned in the upper extremity of the casting.

A still further object of my invention is to provide a construction of electromagnetic driver for sound reproducers wherein adjustment may be made of an electromagnetic operating structure with respect to a driving armature by movement of the electromagnetic structure through variable planes par-

allel to the driving armature for the selection of a desired magnetic gap between the electromagnets and the driving armature for the reproduction of sound of a particular characteristic at maximum efficiency.

Still another object of my invention is to provide a construction of electromagnetic sound reproducer where the electromagnetic operating mechanism is provided with a three point suspension with respect to the driving armature for insuring accurate adjustment of the electromagnetic operating mechanism with respect to the driving armature.

My invention will be more clearly understood by reference to the following specification and the accompanying drawings in which:

Figure 1 is a cross-sectional view taken through the loud speaker of my invention showing the support for the electromagnetic operating mechanism partially in side elevation; Fig. 2 is a view through the loud speaker construction of Fig. 1 looking in the direction of line 2-2; Fig. 3 is an enlarged view of the electromagnetic sound operating mechanism illustrating the 3 point suspension construction in more detail; Fig. 4 is a fragmentary plan view of the electromagnetic operating mechanism showing the arrangement of the parts thereof; Fig. 5 is a view looking in the direction of the driving armature member within the electromagnetic operating mechanism of the cone speaker; and Fig. 6 illustrates the parts which form the control system for regulating the movement of the electromagnetic operating mechanism and controlling the adjustment thereof.

In the manufacture and distribution of cone speakers constructed in accordance with the copending application above referred to, difficulty has been experienced in the assembly of the apparatus by reason of the dual mounting of the conical sound reproducing diaphragm and the electromagnetic operating mechanism. This has required the accurate spacing of the sound reproducing diaphragm support from the support for the electromagnetic driver and the construction has been so fragile that a large percentage of rejections and apparatus returned for repair has resulted. The construction of the cone speaker as set forth herein is the result of research and development after a study

of the operation of thousands of cone speakers manufactured in accordance with said aforementioned application in actual service. I provide a construction of electromagnetic 5 operating mechanism and sound reproducing diaphragm which may be readily assembled within the sound amplifying cabinet with the electromagnetic driving mechanism and the sound reproducing diaphragm mounted 10 upon a single casting. This construction facilitates manufacture, for the complete electromagnetic mechanism and sound reproducing diaphragm may be manufactured and assembled in one place and then mounted 15 within the sound amplifying cabinets in still a different place, permitting the utilization of manufacturing facilities to the greatest advantage. The adjustment which I provide permits the accurate movement of the 20 electromagnetic driving mechanism with respect to the armature for the selection of a magnetic gap of proper size for efficient reproduction of sound of a particular characteristic. The details of the construction of 25 the electromagnetic sound reproducer of my invention will be better understood by detail reference to the drawings wherein reference character 1 designates a base member from which the parts of the sound reproducer are mounted. A cabinet structure 2 entirely encloses the sound reproducing diaphragm and electromagnetic operating mechanism. A vertically extending casting 3 is positioned within the cabinet structure and rests on feet 4, 5, and 6 on the lower portion 30 of the casting through which bolt members 7 pass for anchoring the vertically extending casting 3 firmly to the base. The casting 3 terminates in a circular head portion 8 which is centrally apertured as represented 35 at 9 and counterbored and screw threaded as represented at 10. The apertured portion 9 forms an annular abutment face represented at 11 against which an armature member 12 is arranged to be seated and secured 40 in position by lock ring 14 operating in the screw threads 10. The armature construction which I prefer to employ is set forth more particularly in Letters Patent 45 1,588,545 granted to William H. Gerns, June 50 15, 1926. The armature member may be mounted between gaskets in the manner set forth in Patent No. 1,526,626 granted to Cecil E. Brigham, February 17, 1925. The 55 armature member 12 delivers sound vibrations through a link member 15 to the apex of an elliptical conical shaped sound reproducing diaphragm 16. Connection is made 60 between the link member 15 and the apex of the conical shaped sound reproducing diaphragm by means of members 17 and 18 contacting with opposite surfaces of the sound reproducing diaphragm and secured together as a unit for gripping the apex of 65 the sound reproducing diaphragm by means of a screw chuck connection represented at 19. The screw chuck 19 is in the form of a spring collet device which may grip the link member 15 at any desired point along the 70 length thereof in establishing connection between the armature and the sound reproducing diaphragm. The spring collet chuck enables a quick assembly of the sound reproducing apparatus when manufactured on a 75 quantity production scale.

I provide a pair of extensions 20 and 21 cast integral with the circular portion 8 of the vertically extending casting 3 and on these extensions I secure a pair of supporting members 22 and 23 which terminate at 80 diametrically opposite points of an elliptical shaped rim member 24. The members 22 and 23 are secured to the elliptical rim member 24 along the longest diameter of the rim member as represented at 25 and 26, so that 85 the elliptical rim member 24 has its longitudinal axis extending in a plane coincident with the plane of the vertically extending casting 3. The outer periphery of the elliptical shaped conical diaphragm 16 floats 90 within the elliptical shaped rim 24 through a connection with flexible material 27 secured by a framing rim 28 coinciding with the rim 24 and secured at a plurality of 95 points about its periphery by means of the screw devices or other suitable means as represented at 29. I provide another set of lug members which are cast integral with the vertically extending casting 3 as represented at 30, 31 and 32. These lug members extend from the side of the circular portion 8 and are longitudinally apertured to slidably 100 receive pin members 33, 34 and 35 carried by the plate 36 on which the electromagnetic operating mechanism is mounted. The electromagnetic operating mechanism includes 105 electromagnets 37 and permanent magnetic system 38. The electromagnetic system is provided with laminated pole pieces represented at 39 for reduction in iron losses and 110 securing of maximum efficiency. A non-magnetic plate member 40 is secured across the poles of the permanent magnetic system 38 and to this plate member there is riveted 115 a screw device 41. The screw device 41 may be advanced or retracted in a screw threaded member 42 which is journaled within the bracket member 43 which spans the entire 120 electromagnetic operating mechanism and is secured to diametrically opposite points on the circular casting 8. In order to form a substantial mounting for the spanning member 43 I provide a still further set of lugs 44 and 45 which are cast integral with the cylindrical portion 8 and protrude from opposite sides thereof enabling corresponding 125 extremities 46 and 47 of the spanning member 43 which is bridged across the electromagnetic operating mechanism to be aligned and secured to the lugs 44 and 45 forming 130

a substantial mounting. I provide a retaining member 49 with a set screw therein for securing the internally screw threaded member 42 in position in the journal 43, the screw threaded member 42 being free for rotation without restriction between maximum and minimum limits for the adjustment of the gap between the electromagnetic pole pieces 39 and the driving armature 12.

10 The outer extremity of the internally screw threaded member 42, represented at 50, is cone shaped enabling a tubular member 51 having an internal cone shaped bore to be frictionally gripped thereover and secured in position by means of the screw member 52. The tubular member 51 may thereby be readily applied or secured in position over the extension 50 from the outside of the cabinet when the apparatus is assembled. An operating knob 53 is next positioned by means of a set screw upon the extension rod 51 and the position of the electromagnetic operating mechanism with respect to the driving armature controlled by a sliding 20 movement of the suspension pins 33, 34 and 35 in the cylindrical bores of the lug members 30, 31 and 32 on the cylindrical housing 8.

25 It will be observed that all of the parts of the electromagnetic sound reproducer are mounted from the central vertically extending casting 3 and that for this purpose a plurality of lugs are provided extending in opposite directions and in different planes from the cylindrical portion 8 of the main casting. The ring member 14 by which the armature 12 is secured in position may be slotted at different points about its periphery for permitting a tool to grip and rotate 30 the rim. A spring device 54 is disposed between the adjustable plate member 36 and the ring member 14 for preventing vibration of the parts under continued action of the electromagnetic operating mechanism. The 35 terminals for the electromagnetic system are represented at 55 and a flexible conductor 56 leads from the terminals to the exterior of the cabinet for permitting connection to be made with the output circuit of an amplification system.

40 The action of the screw device 42 is to secure micrometer movement of the member 40 by reason of differential action of the screw 41 which is advanced or retracted in 45 the internal screw threads of the device 42 in accordance with the movement of the control knob 53 from the exterior of the sound amplifying cabinet structure. By reason of the micrometer adjustment extremely accurate magnetic gap clearances may be secured.

45 I have found the construction of cone speaker illustrated in the drawings to be extremely practical for manufacture and 50 production processes and efficient in its elec-

trical operation, and although I have illustrated one of its preferred embodiments I desire that it be understood that modifications may be made and that no limitations upon the invention are intended other than 70 are imposed by the scope of the appended claims.

What I claim as new and desire to secure by Letters Patent of the United States is as follows:

55 1. An electromagnetic sound reproducer comprising a vertically extending casting, an electromagnetic driving mechanism supported by said casting, a plurality of lug members integrally related to the exterior of said casting, an electromagnetic operating mechanism, a frame concentrically arranged within said casting for carrying said electromagnetic operating mechanism, and a plurality of pins extending between said frame and the lug members on said casting whereby said electromagnetic operating mechanism may be slidably adjusted within said casting, a driving armature actuated by said electromagnetic operating mechanism, and a cone shaped sound reproducing diaphragm having its apex connected with said armature whereby mechanical vibrations of said armature impart similar movement to said diaphragm.

60 2. An electromagnetic sound reproducer comprising a base member, a sound amplifying cabinet carried by said base member, a vertically extending casting secured to said base member within said sound amplifying cabinet, an electromagnetic operating mechanism carried by said vertically extending casting, an armature member positioned in said casting, a cone shaped diaphragm and a connection between said armature member and said cone shaped diaphragm, an electromagnetic operating mechanism slidably positioned in said casting, and means controllable from the exterior of said cabinet for adjusting the position of said electromagnetic operating mechanism with respect to said armature for securing maximum efficiency in the reproduction of sound by said cone shaped diaphragm.

65 3. An electromagnetic sound reproducer comprising a base, a sound amplifying cabinet mounted upon said base, a casting carried by said base within said sound amplifying cabinet, a cone shaped diaphragm, said casting providing a housing for an electromagnetic driving mechanism including an armature arranged to impart mechanical vibrations to said cone shaped diaphragm, an electromagnetic operating mechanism for actuating said armature, and means controllable from the exterior of said sound amplifying cabinet for adjusting the spacial relation of said electromagnetic operating mechanism and said driving armature for the reproduction of sound at maximum efficiency.

4. An electromagnetic sound reproducer comprising a base, a sound amplifying cabinet mounted on said base, a vertically extending casting carried by said base interiorly of said amplifying cabinet, said cabinet terminating in a circular head portion forming a housing for an electromagnetic sound reproducing mechanism, a plurality of lug members extending from said circular housing, a cone shaped sound reproducing diaphragm positioned within said cabinet, a driving armature positioned within said circular housing and connected with the apex of said cone shaped sound reproducing diaphragm, an electromagnetic operating mechanism slidably positioned within said circular housing, a rotatable control knob positioned exteriorly of said sound amplifying cabinet, and a screw connection within said sound amplifying cabinet between said control knob and said electromagnetic operating mechanism for imparting translatory motion to said electromagnetic operating mechanism with respect to said driving armature for the reproduction of sound at maximum efficiency.

5. An electromagnetic sound reproducer comprising in combination a supporting base, a vertically extending casting carried by said base, said casting terminating in a cylindrical head, a conical shaped sound reproducing diaphragm, a driving armature positioned within said cylindrical head and connected with the apex of said conical shaped sound reproducing diaphragm, a cylindrical frame having a plurality of pins extending therefrom, said pins projecting into corresponding cylindrical bores in said circular head, and a guide secured to said circular head for advancing or retracting said electromagnetic operating mechanism within said circular head with respect to said driving armature, said pins sliding within said cylindrical bores for aligning said electromagnetic operating mechanism with said driving armature.

6. An electromagnetic sound reproducer comprising a base member, a vertically extending standard on said base member, a housing for an electromagnetic driving mechanism positioned on said standard, a plurality of lug members contiguous with said housing and extending in opposite directions therefrom, connections between a pair of said lug members on one side of said housing and said frame, a conical shaped diaphragm, a driving armature positioned within said housing and connected with the apex of said conical diaphragm, a plate member carrying an electromagnetic operating mechanism arranged to be projected into said housing and variably aligned with said driving armature, a plurality of pin members carried by said plate, said pin members arranged to project into a corresponding

number of lugs on the opposite side of said housing, and a screw device for advancing or retracting said pin members within said last member lugs for fixing the size of said magnetic gap between said electromagnetic operating mechanism and said driving armature.

7. An electromagnetic sound reproducer comprising a base, a member extending from said base and terminating in a housing for an electromagnetic sound reproducer, a sound reproducing diaphragm, a driving armature located in said housing and arranged to impart mechanical vibrations to said diaphragm, a bridge member connected across said housing and electromagnetic operating mechanism, a frame carrying said electromagnetic operating mechanism, a plurality of pins secured to said frame and arranged to be projected through bores formed in said housing, and a screw mechanism carried by said bridge member whereby said frame may be advanced or retracted for adjusting the distance between said electromagnetic operating mechanism and said driving armature.

8. In an electromagnetic sound reproducer the combination of an electromagnetic driving mechanism including a driving armature member, a conical shaped sound reproducing diaphragm, a rod member extending from said driving armature member through the apex of said conical shaped sound reproducing diaphragm, and a spring collet chuck device carried by the apex of said conical shaped reproducing diaphragm for gripping said rod member at a selected point along the length thereof.

9. An electromagnetic sound reproducer comprising a supporting member, a housing for an electromagnetic driving mechanism carried by said supporting member, a conical shaped sound reproducing diaphragm, a driving armature located within said housing and arranged to impart mechanical vibrations to the apex of said conical shaped sound reproducing diaphragm, an electromagnetic operating mechanism slidably positioned within said housing, a bracket member extending from one side of said housing, a screw device journaled in said bracket member, and means for rotating said screw device for imparting translatory movement to said electromagnetic operating mechanism whereby the distance between said electromagnetic operating mechanism and said armature member may be varied.

10. In a loud speaker construction a sound amplifying chamber, an electromagnetic operating mechanism and sound reproducer positioned within said sound amplifying chamber, said electromagnetic operating mechanism having a rotatable adjusting device extending therefrom to a position adjacent the wall of said sound amplifying

- chamber, an extension device arranged to be passed through the wall of said sound amplifying chamber and secured to said rotatable adjusting device and a control knob secured upon said extension device exterior of the wall of said sound amplifying chamber for adjusting said electromagnetic operating mechanism from the exterior of said sound amplifying chamber.
- 10 11. In a sound reproducing apparatus a sound amplifying chamber, an electromagnetic operating mechanism and sound reproducing diaphragm within said chamber, a rotatable device on said electromagnetic operating mechanism for adjusting said 15 mechanism, said rotatable device terminating adjacent the interior wall of said sound amplifying chamber and a tubular member insertable through the wall of said sound amplifying chamber from the exterior of 20 said chamber for gripping said rotatable device and a control knob arranged to be secured on said tubular member exterior of said chamber for adjusting said electromagnetic operating mechanism. 25

In testimony whereof I affix my signature.

HARRY STEVENSON.
